ABSTRACT OF THE DISCLOSURE

ω -Guanidino fatty acid esters of the formula

wherein n is an integer of from 3 to 5 inclusive and R is an alkyl, aryl or arylalkyl group in which the aromatic may or may not be substituted.

This invention relates to novel ω -guanidino fatty acid esters and their production.

The fatty acids as used in the present invention are those fatty acids having 4 to 6 carbon atoms. The ester of such fatty acid is an alkyl, aryl or arylalkyl ester wherein the arylalkyl is a benzyl group which may have or may not have in the aromatic ring such substituent as, for example, a methylol, methoxy, halogen, carboxyl or nitro group.

In order to obtain the guanidino fatty acid esters of the present invention, a guanidino fatty acid is esterified according to the following reaction formula with an alcohol which will give the desired ester mentioned above:

wherein n is an integer of 3 to 5 and R is an alkyl, aryl or arylalkyl group having 1 to 7 carbon atoms and which may be substituted as mentioned above.

The guanidino fatty acid esters of the present invention are basic and therefore are preferable to be separated after converting the same in a salt with an acid which can form a salt with a guanidino base. Examples of such acids are inorganic acids such as hydrochloric acid, sulfuric acid, phosphoric acid or carbonic acid, and organic acids such as oxalic acid, tartaric acid or p-tosyl sulfonic acid.

The ω -guanidino fatty acid esters of the present invention are novel compounds and have action to strongly in-

2

hibit the hydrolysis of alginine ester by kallikrein as shown in the drawing which shows inhibitory effects of guanidino acid esters on hydrolysis of methyl $\text{Na-tosyl-L-arginate}$ by plasma kallikrein. The compounds are therefore useful for a medicine as an antikallikrein agent. Further, the guanidino acid esters of the invention also inhibit the hydrolysis of casein by plasmin. Therefore, the esters are also useful as antiplasmin agents.

The effects of the guanidino fatty acid esters on dogs with experimental pancreatitis were tested by the method of Elliott, D. W. (Ann. Surg. 146,669 1957). Thus, each of amyl δ -guanidinovaleate and benzyl ϵ -guanidinocaproate was intravenously injected in an amount of 5 mg./kg. bodyweight before the operation, and infused in an amount of 100 mg./animal after the operation. The results are as follows:

Effects of guanidino acid esters in dogs with experimental pancreatitis.

20

		Mortality, (percent)	Increase of hematocrit ¹	Serum amylase ²
25	Control.....	66	53	2,750
	Amyl δ -guanidino valerate.....	33	44	2,100
	Benzyl δ -guanidino caproate.....	0	46	1,500

¹ Percent, 24 hours after operation.

² Units, 24 hours after operation.

30

Further the inhibitory effects the guanidino acid esters of the invention on the hydrolysis of methyl $\text{Na-tosyl-L-arginate}$ by plasma kallikrein and on caseinolysis by plasmin are as follows:

40

		Inhibition of hydrolysis, percent ¹			Inhibition of caseinolysis, percent ¹		
		1	2	4	1	2	4
45	Hexyl δ -guanidino valerate.....	33.2	63.0	.....	72.0	85.0	
	Amyl δ -guanidino valerate.....	38.0	² 62.0	.....	71.0	75.3	
50	Benzyl δ -guanidino caproate.....	35.8	53.7	² 70.4	44.2	54.0	.....
	Benzyl δ -guanidino caproate.....	65.3	83.0	.....	34.3	40.5	.....
	p-Carboxybenzyl δ - guanidino valerate.....	37.1	37.1	.....	73.4	94.7	97.2
	p-Carboxybenzyl δ - guanidino caproate.....	35.7	39.9	.....	66.0	79.8	91.5

¹ Concentration of inhibitors, millimoles.

² 5 millimoles.

60 In the administration of the guanidino fatty acid esters of the invention to human being they may be in a suitable form such as capsule, emulsion, powder, injection and tablet.

What I claim is:

1. A compound of the formula

wherein n is the integer 4 or 5, R is benzyl or carboxybenzyl, and X is an acid which is capable of forming a salt with the guanidino base.
